MEANS FOR MOUNTING PROPELLER
BLADES

Hermann Ellinghausen, Bremen, Germany

Application November 21, 1936, Serial No. 112,154
In Germany November 23, 1935

5 Claims. (Cl. 170—159)

The present invention relates to propellers and more particularly to means for fastening the blades of wood propellers to the hub socket.

For some purposes wooden propellers are preferred to the metallic ones. The increase of speed resulting from the steady development of the aeroplanes and which is not yet definitive, on account of the large difference of the starting and service speeds almost generally requires propellers with variable pitch or adjustable blades, and thus a propeller having adjustable wooden blades is of paramount importance in the construction of aeroplanes.

When however the two blades of a wooden propeller are separated from one another with a view to their adjustability the advantage afforded by the high tensile strength of wood in the direction of its fibres will be lost at the hub. On the other hand it has not yet been possible to fasten the wooden blades in the metallic sockets, by means of which the blades are revolvably connected to the hub in the same way as metallic blades, in such a manner that this connection is able to safely and durably stand the centrifugal and vibration forces to which such wooden blades are subjected.

Various systems have already been known which are based on the prospective idea that the centrifugal forces acting in the blade be taken up at as many points as possible; however the manner in which these forces are to be taken up by no means corresponds to the magnitude of the forces developed nor to the conditions of service so that no practical success was secured in this way.

The present invention relates to means for fastening wooden blades in the sockets of air propellers and more particularly adjustable propellers, and the object of the invention is to provide for means by which the centrifugal and vibration forces are taken up in the wooden blades and transmitted therefrom to the blade sockets thereof in a very safe way. This effect is obtained by the fact that the tensile strength of the fibres as lost by the separation of the two blades is replaced by one or several areas resisting to shearing forces in the wood of the blades and the size of which corresponds to the stress undergone, and that according to the invention, such an arrangement is provided for that a uniform stress in the shearing area or areas is ensured without the tensile and bending strength of the wooden blade being thereby adversely affected.

55 In the accompanying drawing Fig. 1 shows a

longitudinal section of a blade, Fig. 2 the blade socket with the stump of the blade in a cross section and Fig. 3 a portion of an anchor in elevation. Referring to the drawing, the fastening arrangement comprises a plurality of round steel rods or anchors *a* uniformly distributed over the cross section of the blade stump, secured by nuts *c* in the socket bottom and having a diameter which is towards the free end reduced in a step-by-step manner, these rods having the highest possible tensile strength and carrying a plurality of round steel washers *b* properly spaced and prevented from being stripped off the rod by the latter being provided with collars obtained by upsetting in a red-hot condition. As these collars are made by upsetting, all fibres of the steel of the rods remain uninjured and transitions of sufficient radii are formed between the collar and the rod proper so that in all cross sections the said rods are not injured and may be fully stressed with the particular permissible stress. As compared with the systems already known this arrangement not only results in a reduction of weight but also prevents both the cross section of the blade stump and the glued joints of the wood lamellas from being materially weakened.

The washers *b* inserted with the steel rods between at least two layers of the wooden blade will subject an imagined wood cylinder to shear, the diameter of which corresponds to that of the particular washer and the length of which corresponds to the distance of two adjacent washers. According to loading tests accomplished, the resistance to shear of such a cylinder surface is so high that as a rule 7 to 8 washers will be sufficient.

As hereinabove described the rods *a* are attached to the socket by means of the nuts *c*. The socket comprises an outer cup-shaped member *e* having an annular flange *h* by means of which the blade may be bolted to the propeller hub. An inner cup-shaped member *f* in the nature of a lining may be provided within the member *e* but such an inner member is not necessary and forms no part of the present invention.

The steel rods are inserted between the layers of the wooden blade with a definite play so that, when the nuts are tightened in order that the anchors comprising the rods and washers are put under tension, these rods are allowed to freely move in their grooves and to integrally transmit the stress to the washers. A new effect acting in the same direction, of the anchors will result

from the loose seating of the washers on the rods and from the rounded shape of the collars (shown at *d*) obtained by upsetting. As it is rather difficult practically to produce the hollow spaces 5 for the washers exactly registering in two adjacent layers of the blades, the mobility of the washers allowing an inclination of them on the anchors will cause a uniform distribution of the pressure over the two adjacent layers without 10 the rod being stressed unilaterally, the rounded collars permitting of a corresponding attitude to the washers.

When at any point of the bedding of an anchor the distance of adjacent seatings in the 15 wood of the blade does not exactly equal the spacing of the washers concerned the result will, on account of the high shearing strength of the cylindrical shearing surface, be a corresponding compression of the wood fibre ends contacting 20 against the pressure surface of the washers and cracking of the wood will take place. In this way again the pressure will be distributed more uniformly over all washers of the anchors.

The design and the bedding of these novel anchors thus largely warrant that tightening the anchors after the blade stump having been introduced into its socket, by uniformly tightening the nuts, will result not only in a uniform initial tension in the various blade and blade stump 30 cross sections but also in an initial tension which is uniformly distributed over the whole length of each anchor and thus also over a correspondingly large portion of the wood of the blade. In comparison with arrangements already known 35 the novel fastening means further distinguishes itself by the fact that the loose bedding of the washers, develops no forces tending to cleave the glued joints.

I claim:

40 1. Supporting means for propeller blades formed of wood laminations which extend in the direction of the length of each blade comprising, a hub socket for receiving the inner end of the blade, metallic tension members extending into the wood blade and secured to said socket, said tension members being uniformly dis-

tributed over the cross section of the blade and each tension member being arranged between two laminations, collars carried by said tension members and a washer adjacent the hub socket side of each collar for engaging two laminations. 45

2. Supporting means for propeller blades according to claim 1 characterized by the features that the washers are tiltably mounted on the tension members.

3. Supporting means for propeller blades according to claim 1 characterized by the feature that the tension members are embedded with play in the adjacent faces of two laminations of the blade. 10

4. Supporting means for propeller blades 15 formed of wood laminations which extend longitudinally in the direction of the length of each blade comprising, a hub socket for receiving the inner end of the blade, metallic tension members extending into the wood blade, said tension 20 members being uniformly distributed over the cross section of the blade and each tension member being arranged between two laminations, means for fastening said tension members to said hub socket, integral collars on said tension 25 members at spaced points along the length thereof, washers mounted on said tension members adjacent the hub socket side of each collar, and said washers engaging equal parts of two laminations. 30

5. Supporting means for propeller blades 35 formed of wood laminations which extend in the direction of the length of each blade comprising, a hub socket for receiving the inner end of the blade, rods extending into the wood blade and through the base of said socket, said rods being uniformly distributed over the cross section 40 of the blade and each rod being arranged between two laminations, means for fastening said rods to said hub socket, arcuate shouldered collars carried by said rods, washers mounted on said rods adjacent each collar and between the collar and the hub socket, and said washers engaging two adjacent laminations whereby each washer may tilt on said arcuate shoulders. 45

HERMANN ELLINGHAUSEN.
